Atty's

UNITED STATES PATENT OFFICE.

AXEL G. GULBRANSEN, OF CHICAGO, ILLINOIS, ASSIGNOR TO GULBRANSEN-DICKINSON COMPANY, OF CHICAGO, ILLINOIS, A CORPORATION OF ILLINOIS.

KEY-SLIP AND FALL-BOARD CONSTRUCTION FOR PLAYER PIANOS.

Application filed February 21, 1918, Serial No. 218,393. Renewed June 23, 1922. Serial No. 570,384.

To all whom it may concern:

Be it known that I, AXEL G. GULBRANSEN, a citizen of the United States, residing at Chicago, in the county of Cook and State 5 of Illinois, have invented a certain new and useful Improvement in Key-Slip and Fall-Board Constructions for Player Pianos (Case 22), of which the following is a full, clear, concise, and exact description, reference being had to the accompanying drawings, forming a part of this specification.

My invention relates to a player piano.

The particular object of the present invention is to provide an improved construction, consisting of a combined key slip and fallboard.

It is customary in player pianos to mount expression levers or controls upon the bed of the piano in front of the keyboard. This 20 is a natural and most convenient location for them and it has been almost universally adopted. However, a smooth and finished piano exterior is highly desirable when the case is closed.

Heretofore these levers or controls have been covered by a key slip hinged at its lower front edge to the upper edge of the bed or table. As this key slip must be highly finished on all sides and must be fashioned 30 or cut out by hand, it has been an expensive piece to manufacture.

According to my invention the key slip is connected to the fallboard. This fallboard and key slip are hinged in such relation that they may be folded up together and swung back out of the way without requiring any additional room in the interior of the case. In this construction the key slip need not be hand fashioned nor need it 40 be highly finished on the rear side.

In order to teach those skilled in the art how to practice my invention, I shall now describe a specific embodiment of my invention in connection with the accompanying drawings, which form a part of the present specification.

The single figure is a fragmentary vertical cross-section of a player piano embodying my invention. I have illustrated only sufficient of the piano case and mechanism to indicate the relation of the improved con-

struction to the rest of the device. The details of the piano action of the player mechanism do not enter into the present invention, so I shall not make detailed mention 55 of them.

The bed 1 is provided with a keyboard 2 of the usual construction, made up of keys for operating the piano action. The keys are pivoted on the balance rail 3 and extend 60 forward to a point adjacent the outer end of the bed.

I have indicated the pneumatics 4 and the tracker box 5, all of which are disposed within the piano casing 6. The front part 65 of the casing 6 comprises the fall shelf 7, which extends forward in a horizontal direction and beneath which fall shelf there is arranged a hinge rail 8. The hinge rail is disposed immediately above the keyboard 70 2 and forms a stationary support or anchorage for the fall board.

The fallboard 9 is of angular cross-section, having a vertical leg extending substantially between the hinge rail 8 and the 75 lower surface of the fall shelf 7. The horizontal leg 11 extends out part way over the keyboard. The two legs 10 and 11 are of substantially the same length measured from the pivot so that when the fallboard 80 is swung about its hinges the leg 11, which is normally horizontal, will stand upright as indicated in dotted lines, and will close the space between the hinge rail 8 and the bottom of the fall shelf 7.

The cover board 12, which is of angular cross-section, similar to the fallboard 9, has a horizontal leg 13 and a depending vertical leg 14. The horizontal leg 13 is pivoted to the horizontal leg of the fallboard, the pivot 90 or hinge being set back from the outer edge of the leg 11, as shown in the drawing, the hinge being set in a recess 15. This construction is provided so that the horizontal leg 11, when swung up into the vertical 95 position will present a clean finished face 16 without exposing the hinges and also to prevent the hinge from striking the bottom surface of the fall shelf.

The control lever 17 is mounted in the 100 bed member 1 in front of the keyboard 2 in convenient position to be grasped by the

hand of the operator of the instrument. A face board, or secondary key slip 18 finishes the front surface of the keyboard 2. This face board lies immediately in front of the 5 keys and just back of the control lever 17.

The key slip 19 is recessed or rabbeted as shown at 20; this recess extending completely along the length of the key slip and being preferably formed in a rabbeting machine, provides room for the control lever 17 or any other levers or buttons which may be disposed at this point. The vertical leg 14 of the cover board 12 and the key slip 19 are hinged together at their inner edge 15 as indicated at 21.

The operation of the device is as follows. When the piano casing is completely closed the parts are in the condition shown in full lines in the figure. When it is desired to 20 open the piano casing for playing of the device, the cover board 12 with the key slip 19 attached is raised by swinging the cover board 12 about its hinge 27 into the dotted line position shown at 26. The key slip 19 25 swings by gravity about its hinges 21 and assumes the position shown in dotted lines at 26. It will be noted that the outside face of the key slip is always turned outward and the rear face of the key slip is not exposed at any time, so that it need not be 30 highly polished. It will be noted that the radial distance of the outermost edge of the key slip 19 from the pivot 25 on the hinge rail 8 is substantially the same as the radial 35 extent of the two limbs of the fallboard 9. Consequently the fallboard with the cover board and key slip nested together can be folded into the inner position as shown in dotted lines in the figure, exposing the keyboard for manual playing or for automatic 40 playing, as may be desired.

If it is desired only to operate the piano automatically the fallboard need not be disturbed as folding of the cover board and 45 the key slip into the position shown at 26 in dotted line, will be sufficient to expose

the control lever 17 to permit the instrument to be operated automatically.

I do not intend to be limited to the precise details of construction as shown and do 50 not intend to be limited to the specified forms and proportions indicated. It is obvious that the corners of the cover board and key slip may be rounded so that they are of curved cross-sections rather than angular 55 cross-sections. The essential requirement is that these parts shall be capable of nesting together and folding out of the way and doing this preferably without exposing the rear and bottom of the key slip 19. 60

I claim:

In a cover device for a player piano keyboard and the control levers thereof, a fallboard having a vertical leg and a horizontal leg of substantially equal length, a cover 65 board of angular cross section having a horizontal leg hinged at its rear edge to the front edge of the fallboard and substantially as long as the horizontal leg of the fallboard, and a depending leg having an 70 unfinished inner face and shorter than the vertical leg of the fallboard, and a key slip having an inner unfinished face hinged to the lower inner edge of said depending leg and of such a length that when folded will 75 extend from said lower edge substantially to the under face of the horizontal leg of said cover board and in front of the inner unfinished face of said cover board, whereby 80 said several members are capable of completely enclosing the keyboard and control levers and of being nested into compact folded relation, and whereby when said members are in nested relation the inner surface 85 of the depending leg of the cover board and the inner surface of the key slip are both hidden from view.

In witness whereof, I hereunto subscribe my name this 18th day of February, A. D. 1918.

AXEL G. GULBRANSEN.
